(57) **CLAIM**

The ornamental design for a fuel tank vent valve assembly, as shown and described.

DESCRIPTION

This application is related to U.S. patent application Ser. No. 13/334,519 filed on Dec. 22, 2011.

FIG. 1 is a top view of a fuel tank vent valve assembly in accordance with the present teachings.

FIG. 2 is a bottom view of the fuel tank vent valve assembly of FIG. 1.

FIG. 3 is a back view of the fuel tank vent valve assembly of FIG. 1.

FIG. 4 is a front view of the fuel tank vent valve assembly of FIG. 1.

FIG. 5 is a side view of the fuel tank vent valve assembly of FIG. 1.

FIG. 6 is a perspective view of the fuel tank vent valve assembly of FIG. 1; and,

FIG. 7 is another perspective view of the fuel tank vent valve assembly of FIG. 1.

The broken line showing portions of the fuel tank vent valve assembly form no part of the claimed design.

The connector protruding from the body of the vent valve is shown broken away to indicate that no specific length is being claimed.
